CASING FOR SPACE HEATERS OR SIMILAR ARTICLES

Roy G. Churan and Robert M. Lawless, Chicago, Ill., assignors to Inland Steel Container Company, Chicago, Ill., a corporation of Illinois

Application September 7, 1949, Serial No. 4,880

Term of patent 14 years

(Cl. D81—19)

To all whom it may concern:

Be it known that we, Roy G. Churan and Robert M. Lawless, citizens of the United States and residents of Chicago, in the county of Cook and State of Illinois, have invented a new, original, and ornamental Design for Casing for Space Heaters or Similar Articles, of which the following is a specification, reference being had to the accompanying drawing, forming a part thereof.

The figure is a front perspective view of a casing for space heaters or similar articles, embodying our new design.

The side of the device not seen in the drawing is substantially similar to the side shown and the back is substantially plain.

We claim:

The ornamental design for casing for space heaters or similar articles, substantially as shown and described.

ROY G. CHURAN.
ROBERT M. LAWLESS.
